MECHANICAL TOOTH BRUSH

Byron E. White, Brattleboro, Vt.

Application June 26, 1935, Serial No. 28,433

3 Claims. (Cl. 15—26)

This invention relates to rotary tooth brushes and has for one of its objects the production of a simple and efficient tooth brush so constructed as to provide a combination of motion for the brush when operated, whereby the teeth and gums will be vibrated throughout, as well as cleansed.

A further object of this invention is the production of a simple and efficient rotary tooth brush which is so constructed as to produce a rotary as well as a reciprocating movement for the brush thereby obtaining a four-way brushing action to not only cleanse but to also thoroughly vibrate and stimulate the gums.

Other objects and advantages of the present invention will appear throughout the following specification and claims.

In the drawing:

Figure 1 is a front elevation of the brush;

Figure 2 is a longitudinal section through the brush showing the parts in an extended position;

Figure 3 is a longitudinal section of the brush showing the parts in a retracted position; and

Figure 4 is a transverse section taken on line 4—4 of Figure 2.

By referring to the drawing it will be seen that 10 designates the casing which consists of an elongated tubular structure tapering toward its outer end opposite the brush supporting portion. 30 This casing 10 is preferably formed of metal or other suitable material and is closed at its outer end by means of a cap or closure member 11. The opposite end of the casing 10 comprises an integral elongated brush guard 12 which is dished 35 or concavo-convex in cross section, the guard being also tapered toward its outer end, and having a reduced or narrowed neck portion 13.

Bearings 14, 15, and 16 are secured within the length of the hollow tubular casing 10, the bearing 14 being mounted near the inner end of the tube, the bearing 15 near the center of the tube, and the bearing 16 being located near the outer end of the casing. The casing 10 is provided with an elongated longitudinally extending slot 17 through which a thumb-piece or operating knob 18 extends, this thumb-piece being adapted to slide longitudinally of the slot 17, as will be hereinafter described.

A brush supporting shaft 19 is journaled within the bearings 14, 15 and 16 and extends longitudinally of the tubular casing 10, as clearly shown in Figures 2 and 3 of the drawing. A coil spring 20 is wound about one end of the brush supporting shaft 19, and is secured, as at 21, to the shaft 19, and at its opposite end to the bearing 16, as at 22. The shaft 19 carries an elongated tapering brush 23 which fits in close proximity to the guard 12, the bristles of the brush 23 extending within the dished guard 12, as indicated in dotted lines in Figure 3.

An operating cord or cable 24 is secured, as at 25, to the brush carrying or supporting shaft 19, and this cable 24 extends through the notch 26 formed in the bearing 14 and may extend through the notch 27 formed in the bearing 15 as the operating knob 18 is reciprocated or moved longitudinally of the slot 17. The cable or cord 24 is secured to the knob 18, as is shown in Figures 2 and 3. This cord or cable 24 is normally coiled about the inner end 28 of the brush supporting shaft 19, as is shown in Figures 1 and 2.

The operation of the device is as follows:—

As the thumb-piece or knob 18 is moved longitudinally of the slot 17 toward the outer end of the casing 10 of the cap 11, the operating cable 24 or cord 24 will move from the position shown in Figure 2 to the position shown in Figure 3, thereby rotating the shaft 19 in one direction as the cable is uncoiled from the inner end 28 of the shaft 19, and this action will cause the coil spring 20 to be wound about the shaft 19, thereby increasing the tension of the spring. As this action occurs, the shaft 19 will also bodily move inwardly of the casing and cause the brush 23 to also move inwardly and longitudinally of the guard 12 from the position shown in Figure 2 to the position shown in Figure 3. As soon as the knob 18 is released from the thumb of the operator, the coil spring 20 will immediately reverse the rotation of the shaft 19 due to its unwinding action and the shaft 19 will rotate in the opposite direction at the same time coiling the cord or cable 24 around the inner end 28 of the shaft 19, and also causing the shaft 19 to return from the position shown in Figure 3 to the position shown in Figure 2. In other words, as the knob 18 is moved toward the cap 11, the spring 20 will be compressed and also coil about the shaft 19 increasing its tension and when the knob 18 is released, the spring 20 will expand and also rotate the shaft 19. This action will cause the brush supporting shaft to first rotate in one direction and move inwardly with respect to the casing 10 and then rotate in the opposite direction at the same time moving outwardly. This will cause the brush to have not only an oscillating action but also a reciprocating movement.

In brushing the teeth the operator may hold the brush by gripping the handle in any suitable

or desired manner, but it is preferable to grasp the handle or casing 10 in the hand between the fingers causing the little finger to coil about the outer end of the handle and the thumb may engage the knob for the purpose of reciprocating the knob within the slot 17, as described above. The restricted neck 13 will permit the operator to place the brush in the mouth in contact with the teeth, either against the front face or the rear face of the teeth, and since the guard is cut away or inset with respect to the front face of the casing 10, this will allow sufficient room to bridge over the lips or side of the mouth. The formation of the guard also will tend to prevent injury to the soft portions of the mouth and to avoid the tendency of pinching the inner portion of the cheek between the brush and the guard.

The various parts may, of course, be constructed to suit the particular desire of the manufacturer with respect to design, but it has been found advisable to construct the various portions to allow the shaft to rotate approximately six revolutions as the operating knob 18 is moved the length of the slot in one direction, and six revolutions when the knob is returned to the opposite end of the slot. At the same time the brush will provide a desired thrust for vibrating and improving the circulation of the blood in the roots of the teeth, a proper vibration being obtained not only by the rotation or oscillation of the brush but also through the reciprocating movement of the brush due to the shifting of the brush longitudinally back and forth within the guard.

By having the handle tapered, as defined, the same may be more easily gripped as pressure is brought to bear upon the operating knob by the thumb, since pressure upon the knob will cause the tapering casing or handle to wedge downwardly into the hand while the handle or casing is being gripped. When the brush is in operation and placed in the mouth for brushing or cleansing the inside surface of the teeth, the tongue by engaging the back of the guard will provide sufficient pressure. When the outside surface of the teeth is being cleansed, the lips will regulate the amount of pressure desired.

Having described the invention, what is claimed as new is:

1. A tooth brush of the class described comprising a casing, a rotating shaft journaled within the casing, a brush head carried by said shaft, a coil spring anchored with respect to the cas-

ing at one end and secured at its opposite end to said shaft, a pull cord coiled about one end of said shaft and secured at one end to said shaft, said shaft being mounted for rotatable as well as reciprocable movement within said casing, and said pull cord being adapted to rotate and bodily move said shaft in one direction within said casing and at the same time cause said spring to coil about to increase its tension and be compressed longitudinally whereby when said pull cord is released said coil spring will automatically unwind for rotating said shaft in the opposite direction and expand longitudinally for bodily and automatically returning said shaft to its original position. 10

2. A tooth brush of the class described comprising an elongated tubular casing, an operating shaft journaled within said casing for rotating and reciprocating movement, a brush head carried by said shaft, said casing having a longitudinally extending slot along one side thereof, an operating member slidably mounted within said slot, a pull cord coiled about said operating shaft and secured at one end to said shaft, said pull cord being secured at its opposite end to said operating member and extending longitudinally of the casing and within the casing, guiding means formed at one end of said casing through which said pull cord extends, a coil spring coiled about one end of said shaft and secured at one end to said shaft and anchored at its opposite end with respect to said casing, said pull cord being adapted to rotate and reciprocate said shaft in one direction whereby said coil spring will be compressed longitudinally, and said coil spring being adapted to rotate the shaft in the opposite direction and expand longitudinally for automatically and longitudinally moving said shaft in the opposite direction when said pull cord is released. 30

3. A tooth brush of the class described comprising a casing, a rotating shaft journaled within the casing, a brush head carried by said shaft, means connected to said shaft for imparting rotary movement and bodily longitudinal movement of the shaft within the casing in one direction, and means engaging the shaft and casing for automatically rotating the shaft in the opposite direction, and also automatically bodily and longitudinally moving the shaft in its opposite direction. 40
